REVERSING TURBINE

James A. Davies, Media, Pa., assignor to Westinghouse Electric & Manufacturing Company, East Pittsburgh, Pa., a corporation of Pennsylvania

Application October 1, 1936, Serial No. 103,475

4 Claims. (Cl. 60—95)

My invention relates to marine turbines having ahead and astern blading and it has for an object to provide means to induce circulation of cooling medium contiguously to the exhaust end of the ahead blading when the turbine is operated astern in order to prevent excessive rise of temperature in the ahead blading.

The problem of excessive temperatures of idly-running turbine blading is encountered in the marine turbine art, this being due to friction of the blading in the stagnant vaporous and gaseous media; and, unless the heat so developed is dissipated with sufficient rapidity, the blading and surrounding parts of the turbine may attain excessive temperatures. It has been observed that, where the exhaust steam from an astern section is discharged so as to flow over the exhaust end of the ahead blading on its way to the condenser, such blading does not attain excessive temperatures, the exhaust steam absorbing heat therefrom and preventing excessive rise in temperature thereof. With a turbine of the double-flow type, wherein the steam flows axially in opposite directions through a pair of ahead blading sections to spaced exhaust chambers, the astern blading is frequently incorporated within one of the chambers and may, therefore, be arranged contiguously to the exhaust end of one of said sections so that steam exhausting at high velocity may pass along said exhaust end of the section to absorb heat therefrom when operating astern; however, if there is no astern blading in the other exhaust chamber, then a stagnant atmosphere of vaporous and gaseous media exists therein with the result that the friction of the other section of the ahead blading may cause excessive rise of temperature in the latter. Accordingly, I propose to locate a steam nozzle in the exhaust chamber of ahead blading, not having astern blading therein, the nozzle being arranged to supply high-velocity steam for passage through the exhaust chamber to the condenser, the steam being directed to circulate over the exhaust end of the ahead blading and absorb heat from the latter.

A further object of my invention is to provide a marine turbine having ahead and astern blading exhausting to a condenser, the casing structures of the turbine and of the condenser, the exhaust end of the ahead blading, and the cooling surface of the condenser providing a circulation chamber for the exhaust end of the ahead blading, together with a tangentially disposed nozzle for supplying steam under high velocity to the chamber for circulation in the latter to

absorb heat from the idly-running blading and to give up the absorbed heat to the condensing surface, when the turbine is operated astern.

These and other objects are effected by my invention as will be apparent from the following description and claims taken in connection with the accompanying drawing, forming a part of this application, in which:

Fig. 1 is a longitudinal sectional view of a turbine incorporating my improvement; and,

Fig. 2 is a transverse sectional view taken along the line II—II of Fig. 1.

Referring to the drawing more in detail, there is shown ahead turbine blading, at 10, and an astern blading, at 11, the blading being carried by the casing or cylinder 12 and by the spindle 13, the ahead turbine blading being, for example, of the double, or opposed, axial flow type supplied with steam through the connection 14 and exhausting steam to the exhaust chambers 15 and 16 communicating with a condenser, at 17, including a shell 18 and condensing surface 19.

As shown, the astern blading, at 11, is arranged so that the high-velocity steam exhausted from the latter passes by the exhaust end 20 of the section 21 on its way to the condenser absorbing heat from the idly-running blading of the section 21 and preventing the latter from rising excessively in temperature.

As the exhaust chamber 16 for the other section 22 of the ahead blading has no astern blading therein, other means is provided for conveying heat developed in the idly-running section 22 to the condenser circulating water. To this end, a nozzle 25 extends tangentially through the turbine casing 12 and into the exhaust chamber 16, the nozzle providing a downwardly-directed jet of high-velocity steam which is deflected upwardly by the condensing surface so as to produce flow in a circuitous manner contiguously to the exhaust end 23 of the blading section 22, heat being absorbed from the latter section by the circuitously-flowing vapors and given up to the condensing surface. Thus, it will be seen that the exhaust chamber 16 and the condensing surface 19 are so constructed and relatively arranged as to provide a circulation chamber for the steam supplied by the tangentially disposed nozzle, circulation being induced by the relative arrangement of the nozzle and of the chamber and being maintained because of the continuous condensation of the steam, a sufficient amount of the latter being deflected upwardly to assure of the circuitous flow referred to.

The nozzle 25 is preferably supplied with steam

from the auxiliary exhaust by means of a conduit 26 having a valve 27. The astern blading is supplied with steam by a conduit 28 having a valve 29. When the valve 29 is opened to render the 5 astern blading operative, steam is also supplied to the nozzle 25 to induce circulation of steam in the exhaust chamber 16 and transfer of heat by such steam from the idly-running blading section 22 to the condensing surface 19, it being 10 understood, as already pointed out, that the exhaust leaving the astern blading is adequate to convey heat developed in the blading section 21 to the condensing surface.

While I have shown my invention in but one 15 form, it will be obvious to those skilled in the art that it is not so limited but is susceptible of various changes and modifications without departing from the spirit thereof, and I desire, therefore, that only such limitations shall be placed 20 thereupon as are imposed by the prior art or as are specifically set forth in the appended claims.

What I claim is:

1. The combination with a turbine having ahead and astern blading and provided with 25 separate exhaust chambers, of condensing means in communication with said exhaust chambers and means for conveying to the condensing means heat developed in the ahead blading when rotated idly and including means for circulating 30 steam contiguously to the exhaust end of the ahead blading and in contact with the condensing means.

2. The combination with a turbine having ahead and astern blading and provided with separate exhaust chambers, of condensing means in communication with said exhaust chambers and means for conveying to the condensing means heat developed due to idle rotation of the ahead 35 blading when the turbine is operated astern and

including means for circulating steam contiguously to the exhaust end of the ahead blading and in contact with the condensing means, and means for rendering said circulating means effective when the turbine is operated astern. 5

3. The combination with a turbine having ahead and astern blading and provided with separate exhaust chambers, of condensing means in communication with said exhaust chambers and means effective when the turbine is operated 10 astern for conveying heat from the idly-running ahead blading to the condensing means and including a nozzle extending tangentially into the exhaust chamber of the ahead blading for discharging a jet of high-velocity steam into said 15 chamber to provide for circulation of steam adjacent to the exhaust end of the ahead blading and in contact with the condensing means.

4. The combination with a turbine having double-flow blading including sections exhausting 20 steam into terminal exhaust chambers and astern blading arranged in one of said chambers, of means providing condensing surface in communication with said exhaust chambers and means for conveying to the condensing surface heat developed by the idly-running ahead blading when the 25 turbine is operated astern to prevent excessive rise in temperature of the ahead blading, said last-named means comprising the arrangement of the astern blading so as to exhaust steam for flow 30 contiguously to the exhaust end of one of the sections of the ahead blading and then to the condensing surface and a nozzle for discharging high-velocity steam into the other exhaust chamber 35 to induce circulation of steam contiguous to the exhaust end of the other section of the ahead blading and in contact with the condensing surface.

JAMES A. DAVIES.
